COUCH

Joseph Martin, Laurelton, N. Y., assignor to
 United States Cabinet Bed Co., Brooklyn, N. Y.,
 a corporation of New York

Application December 10, 1938, Serial No. 244,910

13 Claims. (Cl. 5—38)

This invention relates to combination collapsible couches in general.

Among the objects of the present invention, it is aimed to provide a combination chair bed consisting of a seat portion and an interchangeable back and bed section.

It is still another object of the present invention to provide a collapsible two section couch member which can be folded up either into a back forming section in association with a third seat forming section to form a three section couch, such as a studio couch or, without a third seat forming section, can be folded up into vertical position out of the way against a wall or the like of a sleeping car, airplane or the like.

It is still another object of the present invention to provide a collapsible two section couch member which can be folded up into back forming position with a third seat forming section or cooperate with the third seat forming section to form a three section studio couch which can be combined with one or more similar three section couches to form a wider bed.

It is still another object of the present invention to provide a foldable couch member which can be folded up into vertical position out of the way against a wall or the like and cooperate with a leg member to be extended into horizontal seat forming position.

These and other features, capabilities and advantages of the invention will appear from the subjoined detailed description of specific embodiments thereof illustrated in the accompanying drawings in which

Figure 1 is a transverse section along the line 1—1 of Fig. 5 showing the combination chair couch in chair forming position;

Fig. 2 is a side elevation partly broken away of the combination chair couch in bed forming position;

Fig. 3 is a plan partly broken away of the combination chair couch in bed forming position;

Fig. 4 is a section with the seat section broken away and the interchangeable back and couch forming elements partly opened up in the process of being extended into or out of couch forming position;

Fig. 5 is an enlarged rear view of the combination chair couch in chair forming position;

Fig. 6 is an enlarged fragmental section on the line 6—6 of Fig. 1;

Fig. 7 is a plan view partly broken away illustrative of a plurality of modified couch beds disposed adjacent to one another to form a wide bed;

Fig. 8 is a side elevation of a couch bed with the arms removed disposed in bed formation to constitute a couch bed; and

Fig. 9 is a side elevation of the movable frame members connected to a wall to form a two-section collapsible couch member relative to a wall or the like.

In the embodiment shown in Figs. 1, 2 and 3, the embodiment there illustrated consists of a main seat section A and a two-section interchangeable back and couch member comprising the sections B and C. The section A preferably has a three-sided angle iron frame 1 with the horizontally extending webs 3 and 4 extending inwardly from the upper end thereof and having a flat spring member 2 connected to the horizontal webs 3 and 4 of the frame 1.

To the vertically extending webs of the sides of the frame 1, there are secured the wall members 5 and 6 and to the vertically extending web of the front bar of the frame 1, there is secured the wall member 7. The wall members 5, 6 and 7 are preferably composed of wood and form the base for the fabric covering 8 which extends from the inner sides of the walls 5, 6 and 7 to and around the lower edges of the walls 5, 6 and 7 and then upwardly along the outer faces of the inner spring mattress member 9 where the fabric 8 is secured to the fabric covering 10. The fabric covering 10 in the present instance constitutes the upper face or surface of the spring mattress member 9 and is connected to or forms a part of the same fabric member 11 which constitutes one of the extended faces of the upholstered mattress or pillow section 12.

The fabric member 10 is in turn connected to the fabric member 13 covering the rear face of the inner spring mattress member 9, which member 13 is in turn preferably connected to the fabric 14 forming the lower cover for the mattress member 9. The fabric 11 of the mattress member 12 is in turn connected to the fabric coverings on the sides of the mattress member 12 which are in the usual way connected to the fabric member covering the other extended surface of the mattress member 12.

In seat forming position, the mattress member 12 is preferably swung around the edge 15 between the fabric members 10 and 11 constituting a hinge and positioned on the mattress member 9 with the fabric members 10 and 11 in engagement with one another as shown in Fig. 1.

Extending down from the ends of the front board member 7 and down from the front ends 55 of the side board members 5 and 6, there are pro-

vided angular foot members 16 and 17 which are connected in place by angle iron brackets 18. One web of one bracket 18 extends along the inner face of the front board member 7 and the inner face of the front portion of the foot member 16 and the other web extends along the inner face of the side board member 5 and the inner face of the side portion of the foot member 16.

One web of the other bracket 18 on the other hand extends along the inner face of the front board member 7 and the inner face of the front portion of the foot member 17 and the other web extends along the inner face of the side board member 6 and the inner face of the side portion of the foot member 17. Each of the angle iron brackets 18 is provided with a bracket 19 for the caster or roller 20.

Extending down from the rear ends of the side board members 5 and 6, there are provided the foot members 21 and 22 which are connected to the rear ends of the side board members by the angle iron brackets 23, one web of each of said brackets 23 extending flush with the rear alined faces of the side board member 5 and foot member 21 and flush with the rear alined faces of the side board member 6 and foot member 22 and the other web of each of the other angle iron brackets 23 extending flush with the inner side faces of the side board member 5 and foot member 21, and flush with the inner side faces of the side board member 6 and foot member 22.

To form a support for the rear casters 24 and 25 of the section A, see Fig. 1, and at the same time also a support for the connecting means for connecting the section B and therefore the sections B and C to the section A, there are provided the angle iron brackets 26 constituting frames, see Figs. 4 and 6.

Each of these brackets 26 has one of its webs 27 connected in the present instance by two bolts 28 to the rear web of the angle iron bracket 23 with a spacer 29 between the web 27 and the bracket 23 and a wing nut 30 for removably connecting the bracket 26 in place. The other forwardly extending web 31 of the bracket 26 is provided with a vertically extending slot 32, see Fig. 4, in which slot, there is slidably mounted the pivot pin or bolt 33 connected to the web 34 of the side angle iron bar 35 of the section B.

The lower end of the web 27 is provided with a support 36 for the caster 24, 25. At the upper end of the web 27 and to the rear face thereof, there is secured the bracket 37 having a rearwardly extending abutment 38 to receive the pivot pin 39 secured to the end of the lever 40. The bracket 37 when thus secured to the web 27 constitutes a part of the frame 26.

When now describing sections B and C to facilitate their understanding, their respective parts will be described with reference to their position in bed forming position.

The section B preferably has two side angle iron bars 35 along opposite sides thereof and spaced from one another by the downwardly bent angle iron bar 41 at its front end. The rear ends of the side bars 35 are connected to one another by the angle iron bar 42.

Preferably as shown the inwardly extending webs of the bars 35 have connected thereto the flat spring fabric 43. Preferably also as shown in Fig. 4, a fabric covering 44 extends over the spring fabric 43 and is connected to the downwardly extending webs of the bars 35 and 42.

The downwardly extending webs of the side bars 35 as shown have flat bars 45 pivotally con-

nected to the inner faces thereof, which bars 45 form part of the control linkage in moving the sections B and C into and out of bed forming position and also form supporting legs for the rear end of the section B in bed forming position.

The bars 45 in the present instance are pivotally connected to the free rear ends of the links 40. These bars 45 are also pivotally connected by the links 46 with the flat bars or short links 47 constituting leg elements pivotally connected to the downwardly extending webs of the side bars 48 of the section C.

The front ends of the downwardly extending webs of the bars 48 are pivotally connected to the rear ends of the downwardly extending webs of the side bars 35 and the rear ends of the side bars 48 are connected to one another by the angle iron bar 49, with the flat spring fabric 50 connected to the ends of the inwardly extending webs of the side bars 48.

In the present instance, the rear ends of the links 46 are connected to one another by the angle iron 51 provided with supports 52 at their ends on which are mounted the casters 53.

In the present instance, the embodiment shown in Fig. 1, has the rear ends of the side bars of its frame 1 connected to one another by the downwardly extending angle iron bar 54. Furthermore, the arm rests 55 are provided connected to the side boards 5 and 6 with the fabric 8 between each arm and its side board 5, 6.

As particularly shown in Fig. 4, the rear ends of the horizontally extending webs 3 and 4 of the side bars of the frame 1 are bent upward to form the abutments 56 provided with buttons or stop heads 57. These stop heads 57 serve as limiting stops for the forward inclination of the side bars 35 and therefore of the sections B and C when swung into back forming position, that shown in Fig. 1, when the pivot pins 33 will drop to the bottom of the slots 32 and the arms 37 will serve as limiting stops for the rear inclination of the bars 35, the bars 35 in their vertical position, see particularly Fig. 6, being confined between the abutments 56 and arms 37 and cooperating with the pins 33 then at, or adjacent to, the bottom of the slots 32 to anchor the section B and therewith the section C in erect position. The arms 37 furthermore are engaged by the side bars 35 when the sections B and C are extended into bed forming position, that shown in Fig. 2, when the side of the section B adjacent to section A will rest on, and be supported by, said arms 37.

As particularly shown in Fig. 8, the arm rests 55 may be dispensed with when the sections A, B and C in couch forming position may form a studio couch or as particularly shown in Fig. 7 when the arm rests 55 are omitted two or more of these chair couch combinations may be positioned alongside of one another as A' and A'' to form a bed of any required width.

As particularly shown in Fig. 9, the section A may be dispensed with and the brackets 26 shown in Fig. 4 numbered 126 in this embodiment may be connected to the wall of a room, airplane, sleeping car or the like and the sections B' and C' alone constitute the couch bed. It will be seen that with this arrangement during the day time, the sections B' and C' can be swung into a compact position against the wall out of the way without any auxiliary locking means depending entirely upon the lock formed by the stops 157 and the arms 137 when the pivot pins 133 are in the lower ends of the slots 132.

With the embodiment of Fig. 1, it will be apparent that from the position shown in Fig. 1, it will only be necessary to engage the bars 51 and 49 and pull outwardly on the same into the position shown in Fig. 4, when the pivot pin 33 will rise to the upper ends of the slots 32 whereupon the sections B and C will have inclined outwardly sufficiently to descend by gravity into the position shown in Fig. 2 and in turn from the position shown in Fig. 2, it will only be necessary to engage the rear end of the section C and raise it until the sections B and C fold against one another and the pivot pins 33 again descend to the lower ends of the slots 32 in order to change the device from bed forming position back into chair forming position.

Preferably a loose pillow or upholstered member 58 is positioned on one of its sides on the pillow 12 and rests against the frame of the section B as shown in Fig. 1 in chair forming position, and in bed forming position as shown in Fig. 2, after the frame elements of the sections B and C are stretched out into bed forming position, the pillow 12 will be swung upon its hinge 15 onto the frame of section B and then the pillow 58 placed on the frame of section C to supplement pillow 12 and the spring mattress 9 to form a mattress for the resulting couch bed.

With the embodiment shown in Fig. 9, similarly in order to lower the same into bed forming position, it will only be necessary to engage the outer end of the section C' and the angle iron 151 and pull it outward until the pivot pins 133 ascend to the upper ends of the slots 132 when the sections B' and C' will, by gravity, descend into bed forming position, and in turn in order to close the same from bed forming position, it will only be necessary to engage the outer end of the section C' and raise it until the sections B' and C' fold upon one another and the pivot pins 133 descend to the lower ends of the slots 132 when the sections B' and C' will remain so folded up without the use of any auxiliary locking or anchoring means.

From the foregoing, it will also appear, see Fig. 2 in bed forming position, after the section B has been raised to bring its pivot pins 33 to the upper ends of the slots 32 and the section B has been swung over into the horizontal position shown in Fig. 2, that the portion of the section B adjacent the slots 32, then rests on the abutments formed by the arms 37. Furthermore, it will be seen that in chair forming position when the section B is swung into erect position when the pivot pins 33 descend to the lower ends of the slots 32, the buttons 57 and arms 37 will serve as abutments adjacent to the upper ends of the slots 32 to anchor the section B and therewith the section C in erect position. In other words, the action of the bed illustrated in Fig. 2 is substantially as follows: pulling out and up on the angle irons 51 and 49 pulls the links 40 angularly away from the side bars 35 by the action of the links 46. At the same time the section C pushes upward on the section B. As the links 40 are pulled angularly away from the side bars 35 the links 45 cause the section B to shift vertically with respect to the links 40 as links 40 are pivoted to the fixed pivots 39 at the bottom, and the pins 33 on the side bars 35 are lifted in the slots 32 and slide along the arms 37 away from the abutments 57 when the side bars 35 will finally rest on such arms 37 in a substan-

tially horizontal position. Pull must then be continued on the angle iron 49 while the angle iron 51 is allowed to drop and the legs 52 and casters 53 fall naturally into position. As appears from Fig. 1, however, it will be noted that the side bars 35 of section B decline slightly from the vertical in erect position, shown in Fig. 1 as about three degrees from the vertical, from which it will follow that the moment that the side bars 35 and section B are raised from their lowermost position, the section B may start swinging backward, while sliding along the arms 37 when the upper portion of the side bars 35 will gradually move away from the abutments 57.

It will furthermore appear from the foregoing that any one of a number of combinations are made possible by the present invention.

As an instance:

(a) The section B', see Fig. 9, may alone be used without the section C' when merely a collapsible seat may be formed relative to a side wall and the section B' in erect position would have its pivot pins 133 disposed at the lower ends of the slots 132 and the section B' anchored in erect position between the abutments 157 and 137. On the other hand, in seat forming position, the section B' adjacent the frame 126 would rest on the arms 133 and the other end of the section B' would rest on the leg forming bars 145. The leg forming bars 145 would be connected by the links 140 to the arms 137 so that when the section B' were raised into erect position, the leg bars 145 with the links 140 would be folded up against the section B'. Or else

(b) The sections B' and C', see Fig. 9 could be used without a seat forming section. Or else

(c) The seat section A, see Fig. 2 and the bed section B used without the section C and with or without the arm portions 55, in which case the links 46 and 47 bar 51 and casters 53 will be eliminated and the leg bars 45 alone depended upon to support the outer portion of the section B in bed forming position. Or else

(d) The seat section A used with the bed sections B and C and with or without the arm portions 55 shown in Figs. 1, 2 or 8 as an instance.

It is obvious that various changes and modifications may be made to the details of construction without departing from the general spirit of the invention as set forth in the appended claims.

I claim:

1. The combination of a bracket having a vertically extending slot, an upwardly extending limiting stop, a first bed section having a pivot pin slidably mounted in the slot of said bracket, a second bed section pivotally connected to said first bed section, a pair of short legs pivotally connected to said second bed section, a pair of legs pivotally connected to the first bed section, one pair of links pivotally connecting the short legs of said second bed section with the legs of said first bed section, a second pair of links pivotally connecting the legs of said first bed section with said bracket, said bracket serving as a support for the adjacent end of said first bed section in horizontal position, the bed sections being foldable into erect position with said pivot pin removed from the upper end of said slot and said limiting stop and support anchoring said folded sections in erect position.

2. The combination of a first bed section, a second bed section pivotally connected to said first bed section, a fixed support for one end of said first bed section when in horizontal position and having upwardly extending slots therein, pivot pins on said first bed section slidably mounted in the slots of said support, supports pivotally mounted on said bed sections at points removed from the pivotal connection between said bed sections to supplement said fixed support when the bed sections are in horizontal position, links each pivotally connecting two of said pivotally mounted supports to one another at points removed from the pivotal connections of said pivotally mounted supports with said bed sections, and other links pivotally connecting certain of said pivotally mounted supports at points removed from the pivotal connection of said supports with its bed section to said fixed support whereby the actuation of said bed sections may in one actuation fold said bed sections into erect position and in the other actuation extend said bed sections into bed forming position.

3. The combination of a supporting frame having a vertically extending slot and two abutments on opposite sides of the upper end of said slot, a first bed section having a pivot pin connected to one end of said bed section and slidably mounted in said slot with said first bed section extending upwardly with its pivot pin at the bottom of said slot between said abutments in erect position, a second bed section pivotally connected to the other end of said first bed section, a leg member pivotally connected to said second bed section adjacent its free end, a second leg member pivotally connected to said first bed section removed from said abutments, a link pivotally connecting said leg members to one another, a second link pivotally connecting said second leg member to said frame.

4. The combination of a supporting frame having upwardly extending slots, a first bed section having pivot pins slidably mounted in the slots of said frame, a second bed section pivotally connected to said first bed section, leg members pivotally connected to each of said bed sections, one pair of links pivotally connecting the leg members of said first bed section to the leg members of said second bed section, a second pair of links pivotally connecting the leg members of said first bed section to said frame, a connecting bar fixedly connected to said first pair of links and connecting the leg members of said second bed section to one another to move in unison, casters mounted on the ends of said connecting bar to serve as rolling supports for the end of said second bed section in bed formation, and casters secured to said frame movably to support said frame.

5. The combination of a support having an upwardly extending slot, an intermediate bed section resting on said support in horizontal position and having a pin at one end slidably mounted in said slot, an outer bed section operatively connected at one end to the other end of said intermediate bed section, a leg pivotally connected to said intermediate bed section supplementing said support to support said intermediate bed section in horizontal position, a link pivotally connected to said leg at a point removed from said intermediate bed section and having a pin at its other end pivotally connected to said support near the top of said slot, a second link pivotally connected to said leg at a point re-

5 moved from the pivotal connection of said leg with said intermediate bed section, a second leg element pivotally connected to said outer bed section and pivotally connected to said second link at a point removed from the pivotal connection with said outer section.

10 6. The combination of a bracket having an upwardly extending slot, a limiting stop, a first bed section having a pivot pin slidably mounted in the slot of said bracket, a second bed section, a pair of leg elements pivotally connected to said second bed section at a point removed from the pivotal connection between said bed sections, a 15 pair of legs pivotally connected to the first bed section at a point removed from said bracket, links pivotally connecting the leg elements of said second bed section with the legs of said first bed section, links pivotally connecting the legs of said first bed section with said bracket, and a support on said bracket for the adjacent end of said first bed section in horizontal position, the bed sections being foldable into erect position with said pivot pin removed from the upper end of said slot and said limiting stop and support anchoring said folded sections in erect position.

20 7. The combination of a bracket having an upwardly extending slot, a limiting stop, a first bed section having a pivot pin slidably mounted in the slot of said bracket, a second bed section pivotally connected to said first bed section, a pair of short links pivotally connected to said second bed section at a point removed from the pivotal connection between said bed section, 25 a pair of legs pivotally connected to the first bed section at a point removed from said bracket, a first pair of links pivotally connecting the short links of said second bed section with the legs of said first bed section, a second pair of links pivotally connecting the legs of said first bed section with said bracket, a support on said bracket for the adjacent end of said first bed section in horizontal position, the bed sections being foldable into erect position with said pivot pin removed from the upper end of said slot and said limiting stop and support anchoring said folded sections in erect position, and a cross bar fixed to the outer extremities of said first 30 pair of links to form supporting means for said second bed section.

40 8. The combination of a support having upwardly extending slots therein, a first bed section having pivot pins slidably mounted in the slots of said support, a second bed section pivotally connected to said first bed section, a bracket formed on said support and serving as a support for the adjacent end of said first bed section in bed forming position, a pair of leg elements pivotally connected to each of said bed sections at points removed from the pivotal connection between said bed sections, links pivotally connecting the pair of leg elements of said second bed section to the pair of leg elements 45 of the first bed section, at points removed from the pivotal connections of said leg elements with said bed sections, and other links pivotally connecting the pair of leg elements of said first bed section at a point removed from the pivotal connection of said latter leg elements with said first bed section to said bracket.

50 9. The combination of a bracket having upwardly extending slots, a first bed section having pivot pins slidably mounted in the slots 55 of said bracket, a second bed section pivotally

connected to said first bed section, a support extending from said bracket and supporting the adjacent end of said first bed section in horizontal position, leg elements pivotally connected to said bed sections at points removed from the pivotal connection between said bed sections, and links pivotally connecting said leg elements to one another at points removed from the pivotal connections of said leg elements with said bed sections and to said support.

10. The combination of a frame having a vertically extending slot, an upwardly extending limiting stop, a first bed section having a pivot pin slidably mounted in the slot of said frame, a second bed section pivotally connected to said first bed section, a pair of leg elements pivotally connected to said second bed section, a pair of legs pivotally connected to the first bed section, links pivotally connecting the leg elements of said second bed section with the legs of said first bed section, links pivotally connecting the legs of said first bed section with said frame, a part of said frame serving as a support for the adjacent end of said first bed section in horizontal position, the bed sections being foldable into erect positions where said pivot pin is spaced from the upper end of said slot and said limiting stop and said part of said frame anchors said folded sections in erect position.

11. The combination of a seat section including a bracket having upwardly extending slots therein, an interchangeable back and bed apparatus having a first bed section having pivot pins slidably mounted in the slots of said bracket, a second bed section pivotally connected to said first bed section, a support extending from said bracket to support the adjacent end of said first bed section in horizontal position, leg elements pivotally connected to said bed sections at points removed from the pivotal connections between 40

said bed sections, and links pivotally connecting said leg elements to one another at points removed from the pivotal connections of said leg elements with said bed sections and to said support.

12. The combination of a supporting frame having a vertically extending slot and two abutments on opposite sides of the upper end of said slot, a first bed section having a pivot pin 10 connected to one end of said bed section and slidably mounted in said slot with said first bed section extending upwardly with its pivot pin at the bottom of said slot between said abutments in erect position, a second bed section pivotally 15 connected to the other end of said first bed section, a leg member pivotally connected to said second bed section, a second leg member pivotally connected to said first bed section removed from said abutments, a link pivotally connecting said leg members to one another, a second link pivotally connecting said second leg member to said frame.

13. The combination of a supporting frame, a first bed section, a slot and pin connection connecting one end of said bed section to said frame, abutments on said frame on opposite sides of said slot and pin connection with said bed section disposed between, and confined by said abutments in erect position, a second bed section 25 pivotally connected to the other end of said first bed section, a leg member pivotally connected to said second bed section removed from the pivotal connection between said bed sections, a second leg member pivotally connected to said first bed section removed from said abutments, a link pivotally connecting said leg members to one another, and a second link pivotally connecting said second leg member to said frame.

JOSEPH MARTIN.
